(57) **CLAIM**

The ornamental design for a label printer, as shown and described.

DESCRIPTION

FIG 1 is a perspective view of a label printer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1.

The evenly spaced broken lines immediately adjacent to the shaded areas depict the bounds of the claimed design, while all other evenly spaced broken lines are directed to environment. The dot-dash broken lines indicating an enlargement portion of the design forms no part of the claimed design.
